UNITED STATES PATENT OFFICE.

M JAY SAGE, OF BROOKLYN, NEW YORK.

STRAINER.

1,274,940.

Specification of Letters Patent.

Patented Aug. 6, 1918.

Application filed August 31, 1917. Serial No. 189,127.

To all whom it may concern:

Be it known that I, M JAY SAGE, a citizen of the United States, and a resident of the city of New York, Borough of Brooklyn, in the county of Kings and State of New York, have invented a new and Improved Strainer, of which the following is a full, clear, and exact description.

The object of the invention is to provide 10 a strainer suitable for light liquid hydrocarbons which will prevent any liquid or gas from escaping from the strainer.

The invention is characterized by a casing having an inlet above an outlet, between 15 which a straining surface is interposed, the straining surface being removable through the top of the casing whereat a ground joint is provided to insure against leakage.

This and other characteristics of the invention will appear as the description proceeds.

The figure is a vertical section through a strainer embodying my invention.

The rules of fire underwriters provide 25 that no strainer for gasoline can be used in any building which is not provided with a ground joint at the places giving access to the straining surface of the strainer, and the object of my invention is to comply with 30 those rules and provide such a strainer.

Referring to the drawings, the casing is cylindrical in form and open at the upper end. It has an inlet opening 1 and an outlet opening 2 separated by a partition 3 into 35 which a ring 4 is threaded through the top opening of the casing. The ring 4 has a handle 5 which bridges the ring so as to increase its strength and to facilitate the manipulation of the ring. It has also depending 40 arms 6 extending into the well 7 of the

casing. To these arms a gauze fabric 8 is secured, which constitutes the straining surface.

The top opening of the casing has a valve seat 9, which is preferably cup shape, for a 45 valve 10 which is retained on the seat by a threaded nut 11 which engages an annular shoulder 12 provided on the outside of the valve. The ground valve seat in the strainer prevents any leakage through the top of the 50 strainer.

It will be noted that there is no discharge from the well 7 of the casing, so that no leak can take place thereabout. It will also be noted that the discharge 2 is disposed 55 above the bottom of the well, so that if the lower portion of the straining surface 8 becomes clogged by the sediment in the well, the efficiency of the upper part will not be impaired thereby.

I claim:

A strainer of the class described comprising a cylindrical casing open at one end and having an inlet opening and an outlet opening disposed at different levels, a transverse partition in said casing below the inlet opening and above the outlet opening, a ring threadable into said partition through the end opening of the casing, a member bridging the ring for facilitating the manipulation of same, said ring having arms extending below the partition beyond the inlet opening, a gauze cylinder secured to said arms, a valve closing the end opening of the casing and having an outer annular shoulder, and a nut adapted to have a threaded engagement with the casing and engage the annular shoulder of the valve to secure the same to its seat in the casing.

M. JAY SAGE.
